UNITED STATES PATENT OFFICE

2,551,071

CHILD'S FURNITURE AND TOY
CONSTRUCTION

Anne G. Tyng, Philadelphia, Pa.

Application July 7, 1947, Serial No. 759,324

4 Claims. (Cl. 46—15)

1

The object of the invention is to provide an improved type of toy, that primarily comprises a basic number of different sections, which alone or in multiples of the same can be used for the construction of articles of furniture, toys and the like, of such size that children can use them to support their weight, as distinguished from toys that are merely played with as on a table or equivalent support, or even upon the floor, but which are of such small scale as merely to represent larger articles and devices instead of having utilitarian value per se.

Heretofore there have been many toy sets, which permit their several pieces to be assembled in whole or in part, to represent many mechanical devices such as windmills, Ferris wheels, merry-go-rounds and the like, or with which to build cabins, houses, schools, etc., in miniature, but always to merely represent the corresponding full-sized objects and incapable of supporting the weight of an ordinary child, or for use by a child in his room or in general play in lieu of standard pieces of furniture, etc.

Another and more specific object, therefore, is to provide a set of elements, such as a wheel, a cross brace, horsehead-rocker, black-board panel and longitudinal element, which can be readily assembled to provide such articles as a stool, chair, bench, couch, table, store counter, black-board, rocking horse, wagon, car, horse-on-wheels, pushcart, rocking chair, shelves, bed, house, airplane, etc., two or even more of each element being required for some of said pieces.

From the standpoint of ruggedness and at the same time lightness in weight, it has been found advantageous to cut the several elements of a representative set from sheets of plywood, whether of two-, three-, four-, or even five-ply, or to mold the elements from a non-grained substance such as plastics or the sawdust waste from sawmills, as well as other materials of relatively low cost and abundant supply.

With the objects thus briefly stated, the invention comprises further details of construction and assembly, that are fully brought out in the following description, when read in conjunction with the accompanying drawings, in which Fig. 1 is a plan view of a wheel element comprising one form of such item; Fig. 2 is an enlarged vertical diametrical section through the wheel of Fig. 1, but likewise representing the multi-ply nature of each of said elements; Figs. 3, 4, 5 and 6 are plan views of the horsehead-rocker, cross brace, elongated piece and blackboard elements, respectively; and Figs. 7 to 13 inclusive are perspective

2

views of the blackboard, stool, wagon, chair, table or store counter, bench and rocking horse, respectively.

In Fig. 1 is shown a circular disc 1 of preferably though not necessarily five-ply plywood, as indicated in enlarged cross section in Fig. 2. This disc is provided with a central bore 2 and about its periphery with a plurality of spaced rectangular notches 3, which are preferably four in number. When referring to five-ply plywood, it is to be understood that the invention is by no means limited to this type and thickness, but thus far the five-ply product that is practically standard today has been found to be best suited for the purposes for which said wheel and the other elements are intended. For example, it is sufficiently thick, stiff and rigid to support the weight of a child at least, and to withstand the hard wear and tear to which toy furniture and toys in general are subjected. In the future three-ply, for example, may be strong enough for this purpose, and instead of plywood various substitutes may be used such as molded sawdust, certain plastics and the like, wherefore the term showing of plywood is to be understood as broadly covering any material that can be used in lieu of that which is shown herein.

In Fig. 3 is shown an element 4 which is characterized by the simulation of a horse's head 5, the rear portion of which head is curved to form a rocker edge 6, which in this figure is upon the under side of the head portion. In this position said element presents a horizontal straight or level edge 7, while at the junction of said level edge with said head there is provided a downwardly extending slot 8, a second downwardly extending slot 9 being at the rear of said rocker edge, and a third slot 10 is positioned beneath the rearmost portion of said level edge 7 and extends forwardly and diagonally downwardly into the body of said element, the purposes of these slots being hereinafter described.

In Fig. 4 is shown a cross brace element 11 having an upwardly directed concave edge portion 12 terminating at its opposite ends in a pair of aligned shoulders 13, while in the center of said concave edge portion is a downwardly extending slot 14. The lower portion of said brace element is provided with aligned horizontal surfaces 15, terminating in shallow slots 16 upon the opposite sides of which are protruding feet 17. In Fig. 5 is shown a longitudinal element 18 having a straight edge 19, terminating in shallow slots 20 upon the opposite sides of which are shoulders 21. Adjacent to the lower edge of this element are

two or more apertures through which extend axles 22 with securing pins 23, when said last-mentioned element is used in the construction of an express wagon, such as is shown in Fig. 9.

In Fig. 6 is shown an elongated board-like element 24, which is preferably blacked upon one side surface to provide a so-called blackboard for use with chalk (not shown), either as a toy, an amusement device, or as a means of instructing children with letters, figures, pictures or other such indicia. The four corners of this element are cut out to provide shoulders 25, while the lateral edges 26 are preferably straight and the ends 27 are of any desired shape. It will be noticed that at least some of the various elements are also provided with one or more apertures, which may be of any desired number and arrangement, and through which may be passed twine or wire if desired, as for pulling the wagon (Fig. 9) from place to place, and which aperture in the case of the horse's head serves to suggest an eye.

In considering the present invention, it is to be understood that the preferred set of elements comprises the five pieces herein illustrated and described, but that in order to form some of the possible pieces of furniture and toys it is necessary to employ two or more elements of the same form, type, or class. For example, the bench or blackboard of Fig. 7 requires two of the horse's heads 4, one of the blackboard elements 24 and one elongated element 18, while the stool of Fig. 8 requires one of the wheels 1 and two of the cross braces 11, the latter fitting together in an X-shape. Interchanging the blackboard and elongated elements of Fig. 7 produces a store counter.

Similarly the wagon of Fig. 9 requires four wheels, two elongated elements, one blackboard with its dark surface turned downward if desired, and two cross braces. The chair of Fig. 10 requires two wheels, one horse's head element and one cross brace, while the rocking horse of Fig. 13 requires three horses' heads and two cross braces. The store counter or sloping table of Fig. 11 requires two of the horses' heads, two longitudinal elements and one blackboard, which latter may have its blackened surface turned either upwardly or downwardly. The bench of Fig. 12 by contrast requires one blackboard element, one longitudinal element and two cross braces.

Thus, while seven different pieces of furniture

and toys have been shown, it is to be understood that these are purely illustrative, and merely represent the many others that it is considered unnecessary to illustrate in order to convey the scope of the invention in the wide number and shapes of articles which can be formed or assembled by using the basic elements herein described.

Having thus described my invention, what I claim and desire to protect by Letters Patent of the United States is:

1. A set of elements each element of which has notches into which the other elements are adapted to fit, said set comprising a plurality of flat support panels and a plurality of horsehead rocker elements each comprising in general the silhouette of a horse's head and the back of the neck portion of said element being curved and the top of the head being substantially flat, whereby at least one of said flat support panels may be assembled with said horsehead rocker elements to form a rocking horse in which said curved edges of said horsehead rocker elements are utilized to support said rocking horse and a support panel forms a seat or alternatively said elements may be assembled to form a static piece of furniture in which the flat head portion provides support for the flat panels.

2. A set of elements as defined in claim 1 in which one of said flat panels constitutes a blackboard.

3. A set of elements as defined in claim 1 in which one of the flat panel elements is substantially circular in contour.

35 4. A set of elements as defined in claim 1 made of plywood.

ANNE G. TYNG.
